ATTACHMENT FOR BEER DISPENSING APPARATUS

William Handler, Jerseyville, Ill.

Application November 22, 1934, Serial No. 754,323

2 Claims. (Cl. 225—8)

This invention relates to attachments for beer dispensing apparatus, and in general aims to provide an improved attachment which, while generally similar to the attachment disclosed in 5 U. S. Patent No. 644,171, dated February 27, 1900, results in a superior operation especially with high pressure systems.

In the accompanying drawing illustrating a preferred embodiment of the invention,—

Fig. 1 is an elevation of the attachment shown connected with a beer barrel or keg;

Fig. 2 is a longitudinal section through the attachment shown on an enlarged scale;

Fig. 3 is a perspective view of a part of the 15 attachment shown in Fig. 2; and

Fig. 4 is a perspective view of another part of the same attachment, shown on the same scale.

In the dispensing of beer from barrels under modern conditions, relatively high pressures are 20 used, as compared with the practice of former days. These high pressures are usually maintained substantially uniform by automatic apparatus whose construction is well-known and which it is unnecessary to describe. Nevertheless, the employment of high pressure tends to produce an excessive amount of foam and causes other difficulties when drawing the beer. The present invention provides an attachment, interposed between the outlet of the beer barrel or keg 25 and a pipe or hose line which leads to the faucet, to insure a smooth operation when working with high pressures and to insure the delivery of fresh beer without an excessive amount of foam, with practically no waste at the faucet.

Referring particularly to the drawing, there is shown a beer barrel or keg 5, the top of which is provided with the usual opening (not shown) into which a pipe fitting 6 is secured in any manner known in the art. A hose or pipe 7 is connected 30 to the pipe fitting 6 and also to the carbonating apparatus (not shown) to insure the maintenance of substantially constant pressure of carbon dioxide gas upon the beer in the keg or barrel 5. A shutoff cock 8 is secured to the fitting 6 and provides means for cutting off the barrel 5 from the delivery pipe or hose 9 whenever it is desired to effect repairs in the delivery apparatus or whenever the said hose or pipe is to be cleaned. Between the shut-off cock and the hose or pipe 9 the 35 improved attachment 10 is placed, said attachment preferably being secured by screw-threads 11 to the shut-off cock 8 and being screwed into the end of the hose 9 by means of the screw-threads 12.

The improved attachment comprises a hollow

substantially cylindrical body, as shown in Fig. 2, having integral ears or lugs 13 which facilitate the attachment and disengagement of the member from the stop-cock 8. Secured within the body 10 at the upper end is a nipple 14 providing a shot holder and having an enlarged screw-threaded base 15, by means of which it is attached to the inside of the member 10. The nipple 14 has a length preferably greater than half the length of the member 10 and is cylindrical for approximately half its length and then tapers to a point, as is clearly shown. The pointed end is provided with a plurality of slits 16, each of which is preferably no wider than the thickness of a dime, said slits 16 extending longitudinally of the nipple for the greater part of the length of the same, and they are preferably evenly spaced around the circumference of the nipple. A considerable number of lead shot or BB shot 17 are placed within the interior of the 20 nipple 14 so as substantially to fill the entire interior thereof. If desired, a small number of shot may be employed, especially if the pressure available is such that an objectionable resistance to the flow of the liquid is offered by the larger 25 number of shot. However, with commercial apparatus known to me, the described construction, with the nipple 14 entirely filled with shot, is preferred.

Within the nipple 14 is a smaller nipple 18 30 which is secured as by a screw-threaded shoulder 19 to the interior of the nipple 14. The nipple 18 has longitudinal slits 20 which are preferably of the same width as the slits 16 and which extend for substantially the entire length of said 35 nipple. The nipple 18 is pointed so as to facilitate movement of the nipple 18 into the nipple 14 even when the latter is nearly full of shot 17. Obviously, if the nipple 18 is then screwed into the nipple 14, the shot displaced by the nipple 18 40 will move upwardly and will nearly fill the space surrounding the sides of the nipple 18. Both nipples may be screwed down by means of a spanner wrench, as notches (not shown) may be provided in the collars 15 and 19, respectively, to 45 permit engagement of the spanner wrench with the respective nipples. Thus, the nipples may be easily assembled and may be removed for cleaning or replacement.

The device of the present invention acts as a 50 sort of check valve, and insures delivery to the faucet of fresh, live beer which flows quietly even under the high pressure which is used. Thus drawing of a glass of beer is easy and there is practically no waste. In actual practice, it has 55

been found that the present device works far better under high pressure than the attachment disclosed in the aforesaid United States patent, which issued to me. Actual experiment proves that the present device if adapted for modern high pressure systems, whereas the old device was more of a froth-dissipator, adapted only for low pressure work, such as was common toward the close of the nineteenth century.

10 Obviously, the present invention is not restricted to the particular embodiment thereof herein shown and described. Moreover, it will be clear that the device may be used in the dispensing of liquids other than beer.

15 Having described an embodiment of the invention, what I claim as new and desire to secure by Letters Patent is:—

20 1. An attachment of the character described comprising, in combination, a tubular member having attaching means at opposite ends; a nipple which is detachably connected to the tubular member at one end of said tubular member, said nipple extending for more than half the length of the tubular member and being completely surrounded by the tubular member; a plurality of

shot substantially filling the major part of the interior of the nipple; and a second pointed nipple screwed into the first nipple with its point innermost so that when screwed into place it displaces some of the shot; both nipples having 5 a plurality of slits.

2. An attachment of the character described comprising, in combination, a tubular member; a pointed nipple secured with its point innermost to one end of the tubular member and being of 10 such dimensions that a space is left all around it, within said tubular member; said nipple having a plurality of narrow slits extending longitudinally thereof; a second, smaller nipple secured within the first at the same end which is secured 15 to the tubular member, so that both nipples are removed when the larger nipple is disengaged from the tubular member; the second nipple also being pointed and provided with longitudinal slits; a plurality of shot in the larger nipple; the 20 pointed end of the smaller nipple effecting a displacement of some of said shot when the smaller nipple is secured within the larger.

WILLIAM HANDLER.
